Patented June 18, 1918.

UNITED STATES PATENT OFFICE.

LEWIS A. PAYTON, OF HASKEW, OKLAHOMA.

FLUID-PUMP.

1,269,739.

Specification of Letters Patent. Patented June 18, 1918.

Application filed May 19, 1917. Serial No. 170,292.

To all whom it may concern:

Be it known that I, LEWIS A. PAYTON, a citizen of the United States, residing at Haskew, in the county of Woodward and 5 State of Oklahoma, have invented certain new and useful Improvements in Fluid-Pumps, of which the following is a specification.

This invention relates to fluid pumps and 10 more especially to pumps for use in wells, and has for its objects to produce a pump of great efficiency, durability and capacity. More specifically my object is to produce a pump for compressing air and utilizing such 15 air to effect the delivery of water from a well. With the general objects mentioned in view the invention consists in certain novel and peculiar features of construction and combinations of parts as hereinafter 20 described and claimed; and in order that the invention may be fully understood reference is to be had to the accompanying drawing, in which:

Figure 1, is a front view of the pump embodying my invention, one of the air cylinders and pistons being shown in section and other parts broken away.

Fig. 2 is a side elevation of the pump.

In the said drawing, 1 indicates a pair of 30 air cylinders provided at their lower ends with heads or caps 2, connected by pipes 3 with the heads or caps 4 of a pair of water cylinders 5. The lower ends of the water cylinders are closed by caps 6, having reduced necks 7 equipped with perforated caps 8. 9 are pipe ways extending from cylinder 5 near the lower ends thereof, and the upper ends of said pipes are connected by pipes 10 to a standpipe 11 closed at its upper end by a pipe 12 provided with a delivery spout 13.

The caps 2 of the air cylinders, are provided with upstanding tubular portions 14 providing air-intake ports, and controlling said ports are valves 15 retained in operative 45 relation by cages 16. Similar valves 17 within cages 18, are adapted to control the flow of water through the necks of caps 6, and screens 19 are clamped over the lower ends of the necks 17 by the caps for the purpose of excluding sand and other foreign 50 matter from the water cylinders 5.

Couplings 20 are disposed in the pipe lines 9 and contain valves 21 limited as to upward movement by cross pins 22 of the 55 couplings, said valves being adapted when seated to prevent back flow of water through

their respective pipe ways, that is to retain above them any water which stands in the standpipe below a point hereinafter mentioned. 23 represents a series of bearings 60 for a crank shaft 24, the same being shown as provided with two oppositely projecting cranks 25, respectively connected by piston rods 26, with pistons 27 fitting in the air cylinders 1. Said pistons are of any suitable type, but are preferably provided with cup leathers 28 of sufficient capacity to hold a small quantity of water, this water serving to lubricate the pistons and at the same time hold the cup leathers with an air tight relation to the cylinders and keep the latter cool. To supply the water to the air cylinders for the purpose mentioned, the standpipe is provided with a pair of leak pipes 30 through which a sufficient quantity of water can flow 75 to maintain the desired quantity on the cup leathers.

Assuming that a pump of the character described is lowered into a well, preferably until the water level is above the water cylinders, it will be apparent that the water will seek its level in the standpipe but will fall short of such level in the pipe 3 owing to the fact that air is trapped above it in the cylinders 1. Assuming now that the crank 80 shaft is operated, it will be apparent that the upstroke of the depressed piston will result in the opening of the valve of such cylinder and its charge with air, the descent of the piston in the companion air cylinder will 85 compress air below its respective piston 1 and pipe 3 and thus force water standing in said pipe and its respective cylinder 5 up through the connecting pipe 9 and into the standpipe 11, the controlling valve 21 opening under such pressure, and the respective water controlling valve 17 closing to prevent 90 back flow of water into the well.

As the crank shaft starts on its second half revolution the operations of said air 100 cylinders as described are reversed, so that the piston which charged its cylinder with air, compresses such charge and effects a flow of water from its respective cylinder 5 and pipe way 9 into the standpipe. It will thus 105 be seen that by the use of two air cylinders a constant flow of water into the standpipe and from same when said standpipe is once filled with water, it being understood that each time an air cylinder is charged with air 110 the valve 17 of the respective water cylinder opens to permit water from the well to seek

its level within said cylinder and the respective pipe 3 in order that there may be a charge of water to be dislodged upon the ensuing down stroke of the piston of said cylinder.

5 It will also be apparent that there will be a constant leakage of water from the standpipe through pipe 30 into the air cylinders for the purpose hereinbefore explained.

10 A pump of this character will have a large capacity and need repair at infrequent intervals. There will be little wear upon the air cylinders as no sand can accumulate therein, and the cup leathers are readily accessible for replacement when necessary without dismantling the pump. The water cylinders and connections will seldom need attention, particularly as the screens will guard against the entrance into the water 15 cylinders of particles large enough to effect the operation of the valves—in fact screens may be employed of sufficient fineness to exclude coarse sand.

20 From the above description it will be apparent that I have produced a fluid pump embodying the features of advantage enumerated as desirable, and while I have illustrated and described the preferred form of the invention it is to be understood that I 25 reserve the right to all changes properly falling within the spirit and scope of the appended claims.

I claim:

1. A pump comprising a water cylinder 35 having a check-valve controlled intake, a standpipe connected to said cylinder, a cylinder having a check-valve controlled intake for air, a pipe connecting said cylinder with the water cylinder in a plane above the valve of the latter, a piston for operation in the air cylinder, to charge same with air in one 40 air cylinder, to compress such air in the other

stroke and cause it to force water in the water cylinder to close the intake valve thereof and flow through said standpipe, 45 and a leak pipe to convey water from the standpipe into the upper end of the cylinder having the intake for air.

2. A pump comprising a water cylinder having a check-valve controlled intake, a 50 standpipe connected to said cylinder, a check-valve controlling said standpipe, a cylinder having a check-valve controlled intake for air, a pipe connecting said cylinder with the water cylinder in a plane above the 55 valve of the latter, a piston for operation in the air cylinder, to charge same with air in one stroke and compress such air in the other stroke and cause it to force water in the water cylinder to close the intake valve 60 thereof and flow through said standpipe, and a leak pipe to convey water from the standpipe into the upper end of the cylinder having the intake for air.

3. A pump comprising a pair of water 65 cylinders having intake openings, check-valves controlling said openings, a standpipe, pipes connecting the cylinders respectively with the standpipe, check-valves for said connecting pipes, a pair of cylinders 70 having air intake openings, check-valves controlling said openings, pipes connecting the air cylinders with the water cylinders, pistons in the air cylinders, a crank shaft, connecting rods between the crank shafts 75 and the pistons to operate the latter in reverse directions simultaneously, and leak pipes for conveying water from the standpipe to said cylinders above the pistons thereof.

80 In testimony whereof, I affix my signature.

LEWIS A. PAYTON.
